[57] CLAIM

The ornamental design for a tub for bathing, as shown and described.

DESCRIPTION

FIG. 1 is a right, top, front perspective view of a tub for bathing embodying our new design;

FIG. 2 is a top plan view thereof;

FIG. 3 is a front elevational view thereof, the rear elevational view being a mirror image of the front side shown;

FIG. 4 is a right side elevational view thereof;

FIG. 5 is a left side elevational view thereof;

FIG. 6 is a cross-sectional view taken along line 6—6 of FIG. 2;

FIG. 7 is a cross-sectional view taken along line 7—7 of FIG. 2; and,

FIG. 8 is a cross-sectional view taken along line 8—8 of FIG. 2.

The broken line representation of a hole in FIGS. 1, 2, 5, and 7 is for the purpose of illustration only, and forms no part of the claimed design.
